RESTRAINING DEVICE

Russell D. Hanke and Lawrence E. McDonald, Southgate, Mich., assignors to Penguin Industries, Inc., Parksburg, Pa.

Filed Feb. 28, 1969, Ser. No. 15,968

Term of patent 14 years

Int. Cl. D22—99

U.S. Cl. D22—99

FIG. 1 is a perspective view of a restraining device showing the new design.

FIG. 2 is a side elevational view thereof in the extended position on an enlarged scale.

FIG. 3 is a top plan view thereof in a folded position on a greatly enlarged scale.

FIG. 4 is a top plan view thereof in an extended position on a greatly enlarged scale.

FIG. 5 is a side elevational view thereof in an extended position on a greatly enlarged scale.

The device is broken away in FIGS. 3, 4 and 5 for convenience of illustration.

We claim:

The ornamental design for a restraining device, substantially as shown and described.
